JOURNAL BOX

Donald S. Barrows, Rochester, N. Y., assignor to
 The Symington Company, New York, N. Y., a
 corporation of Maryland

Application October 22, 1928, Serial No. 314,187

15 Claims. (Cl. 308—47)

This invention relates to journal boxes and more particularly to articulated or two piece lids for closing the outer openings therein.

The principal object of my invention, generally considered, is to provide a two piece self-adjusting lid for closing the journal box opening, said lid preferably involving a hood and a lid proper between which a torsion spring is positioned, said spring having a pair of coils normally seated on the hood, an intermediate loop normally engaging the hinge lug and the depending ends of the spring engaging the lid proper, that portion of said lid normally engaging the periphery of the box being provided with gasket or packing means if desired.

Another object of my invention is to provide a two piece lid in which the actuating spring is positioned between the hood and lid proper with the coils of the spring seated on the hood and the free ends thereof resting on the lid proper instead of on the hood, thereby maintaining spring tension between the elements of the lid and preventing rattling even when open.

Another object of my invention is to provide a journal box lid having a hood pivoted thereto adjacent its center for enclosing an associated torsion spring, said spring having coils seated on the hood and extending into depressions on the face of the lid, an intermediate loop portion adapted to engage the hinge lug on the box for holding the lid in open or closed position, the free ends or tails of the spring being supported directly under the fulcrum or pivotal means connecting the hood and lid so that the pressure thereof does not tend to cause relative rotation between lid and hood but rather to stabilize the relation between the parts on account of the length of the bearings for the ends of the spring.

A still further object of my invention is to provide a two piece journal box lid comprising a closure member and a hood or housing member pivoted thereto adjacent the center, said closure member being provided with tabs or lugs hooking over adjacent portions on the hood for limiting relative movement therebetween, whereby when the elements of the lid are assembled the spring can not be removed or replaced as long as the fulcrum pin is in position.

Other objects and advantages of the invention relating to the particular arrangement and construction of the various parts will become apparent as the description proceeds.

Referring to the drawing illustrating my invention, the scope whereof is defined by the appended claims.

Figure 1 is a front elevation of a journal box lid assembly embodying my invention, a portion of the hood or spring housing thereof being broken away to more clearly show the construction.

Figure 2 is a sectional view of the lid assembly and a fragmentary portion of the associated journal box on the line 2—2 of Figure 1, looking in the direction of the arrows.

Figure 3 is a fragmentary end elevational view of the pivot pin or pintle and the adjacent portions of the hood and lid proper, the gasket means alternatively shown on the lid proper of Figure 2 being omitted.

Figure 4 is a fragmentary sectional view on the line 4—4 of Figure 1, looking in the direction of the arrows.

Figure 5 is a fragmentary sectional view corresponding to the lower portion of Figure 2 but showing a modification.

Referring to the drawing in detail, like parts being designated by like reference characters, and first considering the embodiment of my invention illustrated in Figures 1 to 4 inclusive, a portion of a journal box 1 is shown with an ordinary form of hinge lug 2 extending from the upper wall or roof thereof, to which the journal box lid assembly 3 is pivotally connected by means of a hinge pin or pintle 4.

In the present embodiment, the complete journal box lid 3 comprises a closure member or lid proper 5 and a hood or spring housing member or retainer 6 normally disposed substantially parallel thereto, as shown in Fig. 2, said parts being movably or pin connected adjacent the horizontal center line of the lid, as by means of a connecting pin 7, said pin extending through outstanding lugs 8 on the lid or closure portion 5 and the depending correspondingly apertured ends 9 on the housing or hood portion 6. The lid assembly 3 is pivoted to the box by the pintle or pivot pin 4 extending through perforated ears or hinge portions 10 on the hood rather than corresponding portions on the lid proper. Both of the pins 4 and 7 may be headed and locked in position in any desired manner as by having the ends split or bifurcated and expanded in place as indicated at 11 and 12 respectively. The lugs or bearing portions receiving the expanded ends may have the corresponding apertures elongated for properly receiving the separated prongs on the pins, whereby when locked in place, turning of said pins with respect to the corresponding apertured lugs is prevented.

In order to limit or substantially restrict relative movement between the lid of closure member 5 and the hood or housing 6, the hood or housing member 6 is provided with a pair of longitudinal lugs 13 and 14, the outer ends of which are bent or hooked over the top edge of the lid proper 5, as shown in Figure 2, to prevent the lid from being closed so far as to bring the hood into contact with the top edge of the lid proper. The hood or housing member 6 is also provided with a pair of longitudinal lugs 15 and 16, the outer ends of which are bent or hooked over the top edge of the lid proper 5, as shown in Figure 2, to prevent the lid from being closed so far as to bring the hood into contact with the top edge of the lid proper. The hood or housing member 6 is also provided with a pair of longitudinal lugs 15 and 16, the outer ends of which are bent or hooked over the top edge of the lid proper 5, as shown in Figure 2, to prevent the lid from being closed so far as to bring the hood into contact with the top edge of the lid proper.

portion 6 when assembled, the upper edge portion of the lid is desirably formed with stops, projections, tongues or tabs 13 hooking over adjacent portions, such as the lugs or portions offset outwardly to form lateral projections on perforated ears or bearing portions 10, on the housing 6, which lugs project horizontally from the side walls of the hood adjacent the upper edge of the lid.

10 In order to provide for resiliently holding the lid in open or closed position, a torsion spring 14 is normally positioned between the carrier member, hood or housing 6 and lid proper or plate member 5, said spring or resilient means having 15 a pair of coils or helical portions 15 presenting convex surfaces and normally resting on concave or correspondingly curved seat or fulcrum portions 16 on the housing or hood 6, and a lever portion formed as an intermediate loop 17 or upwardly extending straight portions joined at their upper end and desirably formed with a wear plate 18 or anti-friction roller (not shown) for engagement with the hinge lug 2 in the normal manner. The free ends or depending straight 20 tails 19 of the spring preferably engage flat lugs or seats 20 formed on the outer face of the lid 5 directly beneath the connecting pin 7 between the lid and hood. In order not to necessitate positioning of the hood 6 at too great a distance from 25 the lid 5, that portion of the lid adjacent the coils 14 is inwardly depressed or pocketed as indicated at 21 to receive the adjacent portion of said coils.

30 In order to provide for tightly closing the opening of the journal box 1 by means of the lid, without necessitating machining or grinding the joint between the parts, said lid is desirably, but not necessarily, formed with a joint 22 formed by a durable semi-plastic material poured or pressed 35 into a dove-tailed slot formed between inwardly converging flanges 23 on the inner face thereof, or having some equally effective method of anchorage, so that the face thereof may adapt itself to the particular inequalities in the box periphery 40 to which the lid is applied. As an alternative, a gasket 22^a may be inserted in a corresponding slot formed by angular flanges 23^a, said gasket being formed of any usual packing means such as rubber or the like and effectively sealing the joint 45 between the lid 5^a and the box 1^a, as shown in Figure 5.

50 From the foregoing disclosure of my invention, it will be seen that I have provided a two piece resiliently pressed and, therefore, self-adjusting lid for a journal box, which lid involves a closure portion and a hood on spring housing portion between which a torsion spring is normally disposed and which can not be removed while the connecting pin between the parts is in place. On account 55 of having the tails of the spring resting on the lid instead of chairs on the housing, a certain amount of spring tension is maintained between the elements of the lid, thereby preventing rattling even when the lid is open. As the tails of the 60 spring are supported directly beneath the fulcrum or connecting pin between the parts of the lid, the spring pressure thereof does not tend to cause relative rotation between the lid and housing, but rather to stabilize the relation between the two 65 because of the length of the bearing for the spring tails which causes any tendency of the lid to rotate with reference to the housing to be resisted through the lever arm which immediately appears as the tails of the spring are caused to 70 bear on one end of the flat or straight seats. It

therefore follows that with lids constructed as disclosed, the pressure exerted by the tails of the spring will hold the fulcrum joint tight and also hold the lid in correct but yielding relation to the housing, the yielding being necessary to compensate for even a small misalignment of the journal box face and hinge lug. When the lid is open, the correct relation will be maintained and under sufficient tension to prevent rattles.

5 On account of the action of the spring ends or tails on the lid, the upstanding lugs or tabs along the top edge of the lid are theoretically useful only during assembly with the lid housing and spring.

10 The process of assembly is substantially as follows. The lid is laid down flat, the spring dropped into approximate position, the top edge of the housing or hood hooked under the lid tabs and the lower end of the housing is then pressed down until the fulcrum pin can be entered. This 15 method of assembly permits the elimination of terminal shelves for the seats which support the spring ends or tails and holding of the spring in position by a more complete enveloping curved lug on the inside of the housing. It will also be 20 noted that the spring can not be removed or replaced as long as the fulcrum pin is in position, which is obviously advantageous in preventing 25 theft or tampering with the lid.

30 Although I have described in detail preferred forms of my invention, it will be understood that I am limited only by the scope of the appended claims.

35 Having now described my invention, I claim:

1. In combination, a journal box having a hinge lug, a lid assembly pivotally carried thereby and comprising a retainer and a lid proper movably connected adjacent the center of the latter, and resilient means engaging the retainer intermediate the ends and with straight transversely spaced lower arms engaging the lid proper and an upper arm engaging the hinge lug.

40 2. In combination, a journal box having a hinge lug, an articulated lid pivotally carried thereby and comprising a hood and a lid movably connected adjacent the center of the latter, and resilient means disposed between said hood and lid engaging the lug and lid respectively at its upper and lower ends and the hood intermediate 45 said ends, the resilient means having lower ends 50 spaced and engaging the lid to stabilize the relation between the lid and the hood.

55 3. In combination, a journal box having a hinge lug, a two piece lid pivotally carried thereby and comprising a retainer connected to the lug by a pin and a closure member connected to the retainer by another pin, and resilient means disposed between and engaging said retainer and a seat on said closure member, straight longitudinally of the resilient means, immediately between the retainer-closure member pin and the plane of said closure member and adapted to engage angularly disposed portions of the hinge lug for holding said lid in open or closed position.

60 4. In combination, a journal box having a hinge lug, a two piece lid pivotally carried thereby and comprising a hood pivoted to the lug adjacent its upper edge and to the lid proper adjacent its lower end, means extending from the upper edge of said lid proper and normally overlying the adjacent portion of the hood for limiting relative movement therebetween, and resilient means disposed between said hood and lid proper

and engaging said lug for holding the lid in open or closed position.

5. In combination, a journal box having a hinge lug, a lid assembly pivotally carried thereby and comprising a hood and a lid proper movably connected adjacent the center of the latter, and a torsion spring disposed between said hood and lid proper and comprising a spring wire formed into a pair of coils seated on the hood, a 10 loop portion extending upwardly therebetween and normally engaging the hinge lug, the ends of said wire extending downwardly from the coils and resting on the lid proper, thereby maintaining spring pressure between the parts of the lid 15 assembly even when opened.

6. In combination, a journal box having a hinge lug, a lid assembly pivotally carried thereby comprising a hood and a lid proper movably connected adjacent the center of the latter and a torsion 20 spring disposed between said hood and lid and provided with coil portions seated on the hood, an intermediate loop portion engaging the lug and the free ends or tails of the spring engaging the lid proper directly beneath the points of connection 25 between said lid and hood, whereby relative rotation therebetween is not caused by said pressure.

7. In combination, a journal box having a hinge lug, a lid assembly pivotally carried thereby and comprising a hood pin connected to the lug adjacent the upper end thereof and pin connected to the lid adjacent its lower end, a torsion spring with a plurality of coils seated on the hood and received in a depression in the lid proper, a loop 35 portion of the spring between the coils normally engaging the lug, and tabs extending from the upper edge of said lid proper and overlying corresponding portions of the hood for limiting angling therebetween, whereby said spring can 40 not be removed or replaced while the fulcrum pin between the hood and lid is in position.

8. A journal box lid assembly, comprising a hood and a lid proper connected adjacent the center of the latter, tabs extending from the 45 upper edge of the lid proper and overlying adjacent portions of the hood for limiting relative movement therebetween, and resilient means held between said hood and lid and formed with an upper extension adapted to engage an associated 50 hinge lug for holding the lid in open or closed position.

9. A journal box lid assembly comprising a hood and a lid proper movably connected adjacent the center of the latter, and resilient means engaging 55 the hood intermediate the ends and with straight extensions on the lower end engaging flat seats on the lid proper to stabilize the relation between the latter and the hood.

10. A two piece journal box lid comprising a retainer adapted to be connected to an associated journal box, a closure member movably connected to the retainer and normally disposed substantially parallel thereto, and resilient means disposed between and engaging said closure member 60 and retainer, and adapted to engage angularly disposed portions on the associated box for holding said lid in open or closed position, the engage-

ment between the resilient means and closure member being along a substantial length of the resilient means to yieldingly maintain the normal relationship between said member and retainer.

5
11. A journal box lid assembly comprising a spring retainer and a lid proper movably connected adjacent the center of the latter, and a torsion spring disposed between said retainer and lid proper and comprising a spring wire formed 10 into a pair of coils seated on the retainer, a loop portion extending upwardly therebetween and adapted to engage an associated hinge lug, the ends of said wire extending downwardly from the coils and resting on the lid proper thereby maintaining spring tension between the parts of the lid assembly.

12. A journal box lid assembly comprising a hood and a lid proper movably connected adjacent the center of the latter and a torsion spring 20 disposed between said hood and lid and provided with coil portions seated on the hood, an intermediate upwardly extending loop portion and the free ends or tails of the spring engaging the lid proper directly beneath the points of connection 25 between said lid and hood, whereby relative rotation therebetween is not caused by said pressure.

13. A two-piece journal box lid comprising a retainer adapted to be movably connected to an associated journal box, a closure member connected to said retainer and normally disposed substantially parallel thereto, and resilient means disposed between and engaging said closure member and retainer and adapted to engage angularly disposed portions on the associated box for 35 holding said lid in open or closed position, the engagement between the resilient means and closure member being along a substantial length of said closure member, the engagement between said resilient means and retainer being along 40 vertically curved surfaces to allow for adjusting movement, and the connection between said closure member and retainer also allowing for adjusting movement.

14. An articulated cover assembly for journal 45 boxes comprising a lid, a hood overlying the upper portion of the lid and provided with side walls having portions thereof offset outwardly to form lateral projections, stop members formed integral with the upper portion of the lid and 50 overlying said projections for limiting relative movement between said lid and hood, and means pivotally connecting the lower side wall portions of the hood to the central portion of the lid.

15. An articulated cover assembly for journal 55 boxes comprising a lid, a hood pivotally secured to the lid, a substantial distance below the upper edge of the lid, lugs projecting from the side walls of the hood adjacent the upper edge of the lid, and projections carried by the lid adjacent its 60 upper edge, said projections being in the form of stops overlying said lugs for limiting relative movement between said lid and hood, said hood being provided with pintle receiving openings beyond the upper edge of the lid.
